Primary Examiner — Holly E Thurman(74) *Attorney, Agent, or Firm* — Haynes and Boone, LLP(57) **CLAIM**

The ornamental design for a gimbal handling device, as shown and described.

DESCRIPTION

FIG. 1 is a front, left, and top perspective view of a gimbal handling device embodying our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front, left and top perspective view thereof, shown with the flap in a raised condition of use.

The stippling in the figures is shown for the purpose of illustrating surface shading of the claimed design. The broken lines in the figures are shown for the purpose of illustrating portions of the gimbal handling device or environmental matter that form no part of the claimed design.
